Patented Jan. 13, 1976

238,453

HAIR GROOMER ATTACHMENT

Joseph Kata, New Haven, and Martin J. Wolff, West Haven, Conn., assignors to Sperry Remington, Sperry Rand Corporation, Bridgeport, Conn.

Filed Oct. 1, 1973, Ser. No. 402,454

Term of patent 14 years

Int. Cl. D28—03

U.S. Cl. D86—10 F

Fig. 2.

Fig. 4.

Fig. 3.

*Fig. 6.**Fig. 5.**Fig. 7.*FIG. 1 is a front side, and right end perspective view of a hair groomer attachment showing our new design, the broken line disclosure of a hair groomer being for illustrative environmental purposes only;

FIG. 2 is, on an enlarged scale, a top plan view;

FIG. 3 is, on an enlarged scale, a front side elevational view;

FIG. 4 is, on an enlarged scale, a right end elevational view;

FIG. 5 is, on an enlarged scale, a rear side elevational view;

FIG. 6 is, on an enlarged scale, a left end elevational view; and

FIG. 7 is, on an enlarged scale, a bottom plan view thereof.

We claim:

The ornamental design for a hair groomer attachment, substantially as shown and described.
